UNITED STATES PATENT OFFICE.

JULIUS B. WANTZ, OF OAK PARK, ILLINOIS, ASSIGNOR TO VICTOR X-RAY CORPORATION, OF CHICAGO, ILLINOIS, A CORPORATION OF NEW YORK.

DESIGN FOR AN ELECTROMEDICAL CABINET.

Application filed April 13, 1928. Serial No. 26,307. Term of patent 14 years.

To all whom it may concern:

Be it known that I, JULIUS B. WANTZ, a citizen of the United States, residing at Oak Park, Illinois, have invented a new, original, and ornamental Design for Electromedical Cabinet, of which the following is a specification, reference being had to the accompanying drawing, in which—

Figure 1 is a top view of an X-ray cabinet embodying such ornamental design; Figure 2 is a front view thereof; and Figure 3 is a side view thereof.

I claim:

The ornamental design for an electromedical cabinet, as shown.

JULIUS B. WANTZ.
